Primary Examiner — Patricia A Palasik(74) *Attorney, Agent, or Firm* — Baker & Hostetler LLP(57) **CLAIM**

The ornamental design for a hot melt dispenser, as shown and described.

DESCRIPTION

FIG. 1 is a top perspective view of a hot melt dispenser according to a first embodiment;

FIG. 2 is a left side view thereof;

FIG. 3 is a right side view thereof;

FIG. 4 is a front end view thereof;

FIG. 5 is a rear end view thereof;

FIG. 6 is a top end view thereof; and

FIG. 7 is a bottom end view thereof.

FIG. 8 is a top perspective view of a hot melt dispenser according to a second embodiment;

FIG. 9 is a left side view thereof;

FIG. 10 is a right side view thereof;

FIG. 11 is a front end view thereof;

FIG. 12 is a rear end view thereof;

FIG. 13 is a top end view thereof; and,

FIG. 14 is a bottom end view thereof.

The broken lines and the areas inside the broken lines depict unclaimed environmental subject matter.

1 Claim, 10 Drawing Sheets(56)
